UNITED STATES PATENT OFFICE.

STEWART H. CRAMPTON, OF NEW YORK, N. Y.

CABLE-CLIP.

No. 890,125.

Specification of Letters Patent.

Patented June 9, 1908.

Application filed October 30, 1907. Serial No. 399,967.

To all whom it may concern:

Be it known that I, STEWART H. CRAMPTON, a citizen of the United States, and resident of the city, county, and State of New York, have made certain new and useful Inventions Relating to Cable-Clips, of which the following is a specification, taken in connection with the accompanying drawings, which form a part of the same.

10 This invention relates to cable clips and relates especially to one piece metallic clips for suspending telephone or similar cables from messenger cables.

15 In the accompanying drawing showing an illustrative embodiment of this invention and in which the same reference numeral refers to similar parts in the several figures, Figure 1 is a perspective showing the clip in position. Fig. 2 is a similar transverse sectional view. Fig. 3 is an enlarged view showing the clip before being applied to a cable.

20 In the illustrative embodiment of this invention shown in the drawings, the clip may, be formed of a single piece of sheet metal, such as zinc, aluminum alloy, or other strong ductile flexible material not subject to corrosion under the conditions of use. The head 5 of the clip may be connected with the body 3 by the tapering portion 6 and the head may, 25 if desired, be formed with a suitable transverse slot 9 with which a narrower locking recess 4 communicates at its upper edge. In this way, the locking shoulders 8 are formed and these shoulders may, if desired, be stiffened 30 and reinforced by doubling over and forcing down the material removed from the ends of the slot so as to form doubled reinforced shoulders at these points. In a similar way the tongue 7 cut from the head in making the 35 locking recess 4 may be bent up and forced down against the sheet of metal which forms the head so as to form a doubled reinforced abutment at this point. This bending and compression of the sheet metal at the edge of the shoulders and abutment of course hardens and stiffens the same so as to give a 40 greatly increased strength at this point in resisting tearing. If desired, also, the end 12 of the body or strap 3 of the clip may be 45 similarly stiffened by doubling back the terminal portion upon itself, this being preferably done in such way that the inturned terminal portion comes on the inside of the

curved suspender or hook 14 when the clip is applied, as is indicated in Fig. 2.

55 These clips may be very readily applied to a cable by passing the body or strap 3 around the cable 2 and then passing it through the slot 9. The end 12 of the clip is then passed around the messenger cable 1 and brought 60 down through the slot until the proper notches 11 come opposite the locking recess into which the reduced neck between these notches slips. The end 15 of the clip is then 65 bent upward around the head so that a hook-shaped suspender 14 may be produced, as indicated in Fig. 2. The strap 3 is normally forced into engagement with the shoulders 8 by the weight of the cable, although these parts are shown slightly separated in Fig. 2 70 for the sake of clearness. In this way, the suspender is prevented from coming out of the locking slot and a still more reliable suspension is secured. By having a number of locking notches, such as 10, 11, in the strap 75 end the clip may be used with cables of varying size and still have the cable brought up as close to the messenger as may be desired.

Having described this invention in connection with an illustrative embodiment 80 thereof, to the details of which disclosure the invention is not, of course, to be limited, what is claimed as new and what is desired to be secured by Letters Patent is set forth in the appended claims.

85 1. The sheet metal cable clip having a head provided with a slot and doubled reinforced shoulders at the upper edge of said slot formed by doubling over the metal removed from said slot against the metal of the head, there being a locking recess in said head communicating with the upper edge of said slot and provided with a doubled reinforced abutment formed at its upper edge by doubling back the metal removed from 90 said slot against the metal of the head, and having connected to said head an integral strap adapted to pass through said slot and formed with a doubled stiffened end and provided with a plurality of locking notches in 95 said doubled end to coöperate with said locking recess.

100 2. The sheet metal cable clip having a head provided with a slot and reinforced shoulders at the upper edge of said slot formed by bending over the metal removed 105

from said slot, there being a locking recess in
said head, communicating with the upper
edge of said slot and provided with a rein-
forced abutment formed at its upper edge by
5 bending back the metal removed from said
recess and having connected to said head a
strap adapted to pass through said slot and

formed with an end provided with a plurality
of locking notches to coöperate with said
locking recess.
